US0D1094396S

(12) **United States Design Patent** (10) Patent No.: **US D1,094,396 S**
 Alee et al. (45) Date of Patent: ** Sep. 23, 2025

(54) **DISPLAY SCREEN OR PORTION THEREOF WITH A GRAPHICAL USER INTERFACE**

(71) Applicant: **Schlumberger Technology Corporation**, Sugar Land, TX (US)

(72) Inventors: **Aaron Alee**, Lysaker (NO); **Matthew Ellwood**, Oxford (GB); **Shaan Dhumale**, London (GB); **Arnaud Levannier**, Prades-le-Lez (FR); **Stewart Smith**, Stavanger (NO); **Surender Manral**, Stavanger (NO); **Guido van der Hoff**, Tananger (NO); **Virginia Raoul**, Lysaker (NO); **Nadia Shafarenko**, Lviv (UA)

(73) Assignee: **Schlumberger Technology Corporation**, Sugar Land, TX (US)

(**) Term: **15 Years**

(21) Appl. No.: **29/866,559**

(22) Filed: **Sep. 19, 2022**

(51) LOC (15) Cl. **14-04**

(52) U.S. Cl.

(57) **CLAIM**

The ornamental design for a display screen or portion thereof with a graphical user interface as shown and described.

DESCRIPTION

FIG. 1 is a front view of a display screen or portion thereof with graphical user interface showing a first image in a sequence of our new design in accordance with a first embodiment;
FIG. 2 is a front view of a second image in the sequence of the first embodiment;
FIG. 3 is a front view of a third image in the sequence of the first embodiment;
FIG. 4 is a front view of a fourth image in the sequence of the first embodiment;
FIG. 5 is a front view of a fifth image in the sequence of the first embodiment;
FIG. 6 is a front view of a sixth image in the sequence of the first embodiment;
FIG. 7 is a front view of a seventh image in the sequence of the first embodiment;
FIG. 8 is a front view of an eighth image in the sequence of the first embodiment;
FIG. 9 is a front view of a ninth image in the sequence of the first embodiment;
FIG. 10 is a front view of a tenth image in the sequence of the first embodiment;
FIG. 11 is a front view of an eleventh image in the sequence of the first embodiment;
FIG. 12 is a front view of a twelfth image in the sequence of the first embodiment;
FIG. 13 is a front view of a thirteenth image in the sequence of the first embodiment;
FIG. 14 is a front view of a fourteenth image in the sequence of the first embodiment;
FIG. 15 is a front view of a fifteenth image in the sequence of the first embodiment;
FIG. 16 is a front view of a first image in the sequence in accordance with a second embodiment;
FIG. 17 is a front view of a second image in the sequence of the second embodiment;
FIG. 18 is a front view of a third image in the sequence of the second embodiment;
FIG. 19 is a front view of a fourth image in the sequence of the second embodiment;
FIG. 20 is a front view of a fifth image in the sequence of the second embodiment;
FIG. 21 is a front view of a sixth image in the sequence of the second embodiment;
FIG. 22 is a front view of a seventh image in the sequence of the second embodiment;
FIG. 23 is a front view of an eighth image in the sequence of the second embodiment;
FIG. 24 is a front view of a ninth image in the sequence of the second embodiment;
FIG. 25 is a front view of a tenth image in the sequence of the second embodiment;
FIG. 26 is a front view of an eleventh image in the sequence of the second embodiment;
FIG. 27 is a front view of a twelfth image in the sequence of the second embodiment;
FIG. 28 is a front view of a thirteenth image in the sequence of the second embodiment;
FIG. 29 is a front view of a fourteenth image in the sequence of the second embodiment;
FIG. 30 is a front view of a fifteenth image in the sequence of the second embodiment;

FIG. 31 is a front view of a sixteenth image in the sequence of the second embodiment;
FIG. 32 is a front view of a seventeenth image in the sequence of the second embodiment;
FIG. 33 is a front view of an eighteenth image in the sequence of the second embodiment;
FIG. 34 is a front view of a nineteenth image in the sequence of the second embodiment;
FIG. 35 is a front view of a twentieth image in the sequence of the second embodiment;
FIG. 36 is a front view of a twenty-first image in the sequence of the second embodiment;
FIG. 37 is a front view of a first image in the sequence in accordance with a third embodiment;
FIG. 38 is a front view of a second image in the sequence of the third embodiment;
FIG. 39 is a front view of a third image in the sequence of the third embodiment;
FIG. 40 is a front view of a fourth image in the sequence of the third embodiment;
FIG. 41 is a front view of a fifth image in the sequence of the third embodiment;
FIG. 42 is a front view of a sixth image in the sequence of the third embodiment;
FIG. 43 is a front view of a seventh image in the sequence of the third embodiment;
FIG. 44 is a front view of an eighth image in the sequence of the third embodiment;
FIG. 45 is a front view of a ninth image in the sequence of the third embodiment;
FIG. 46 is a front view of a tenth image in the sequence of the third embodiment;
FIG. 47 is a front view of a first image in the sequence in accordance with a fourth embodiment;
FIG. 48 is a front view of a second image in the sequence in accordance with a fourth embodiment;
FIG. 49 is a front view of a third image in the sequence in accordance with a fourth embodiment;
FIG. 50 is a front view of a fourth image in the sequence in accordance with a fourth embodiment;
FIG. 51 is a front view of a fifth image in the sequence in accordance with a fourth embodiment;
FIG. 52 is a front view of a sixth image in the sequence in accordance with a fourth embodiment;
FIG. 53 is a front view of a seventh image in the sequence in accordance with a fourth embodiment;
FIG. 54 is a front view of an eighth image in the sequence in accordance with a fourth embodiment;
FIG. 55 is a front view of a ninth image in the sequence in accordance with a fourth embodiment;
FIG. 56 is a front view of a tenth image in the sequence in accordance with a fourth embodiment;
FIG. 57 is a front view of an eleventh image in the sequence in accordance with a fourth embodiment;
FIG. 58 is a front view of a twelfth image in the sequence in accordance with a fourth embodiment;
FIG. 59 is a front view of a thirteenth image in the sequence in accordance with a fourth embodiment; and,
FIG. 60 is a front view of a fourteenth image in the sequence in accordance with a fourth embodiment.
For each of the embodiments, broken lines are illustrative of portions of the graphical user interface that form no part of the claimed design. The outermost broken line rectangle illustrates a display screen or portion thereof, and forms no part of the claimed design.

For each of the embodiments, the process or period in which one image transitions to another image forms no part of the claimed design.
